(57) **CLAIM**

The ornamental design for an instrument panel, as shown and described.

DESCRIPTION

FIG. 1 is a front-facing perspective view of an instrument panel showing a first embodiment of our design;

FIG. 2 is a rear-facing perspective view of the instrument panel of FIG. 1;

FIG. 3 is a rear-facing, exploded perspective view of the instrument panel of FIG. 1;

FIG. 4 is a front view of the instrument panel of FIG. 1;

FIG. 5 is a top view of the card module of FIG. 1;

FIG. 6 is a bottom view of the card module of FIG. 1;

FIG. 7 is a left view of the card module of FIG. 1;

FIG. 8 is a right view of the card module of FIG. 1;

FIG. 9 is a front-facing perspective view of another instrument panel showing a second embodiment of our design;

FIG. 10 is a rear-facing perspective view of the instrument panel of FIG. 9;

FIG. 11 is a rear-facing, exploded perspective view of the instrument panel of FIG. 9;

FIG. 12 is a front view of the instrument panel of FIG. 9;

FIG. 13 is a top view of the card module of FIG. 9;

FIG. 14 is a bottom view of the card module of FIG. 9;

FIG. 15 is a left view of the card module of FIG. 9;

FIG. 16 is a right view of the card module of FIG. 9;

FIG. 17 is a front-facing perspective view of another instrument panel showing a third embodiment of our design;

FIG. 18 is a rear-facing perspective view of the instrument panel of FIG. 17;

FIG. 19 is a rear-facing, exploded perspective view of the instrument panel of FIG. 17;

FIG. 20 is a front view of the instrument panel of FIG. 17;

FIG. 21 is a top view of the card module of FIG. 17;

FIG. 22 is a bottom view of the card module of FIG. 17;

FIG. 23 is a left view of the card module of FIG. 17;

FIG. 24 is a right view of the card module of FIG. 17;

(Continued)

FIG. 25 is a front-facing perspective view of another instrument panel showing a fourth embodiment of our design; FIG. 26 is a rear-facing perspective view of the instrument panel of FIG. 25;

FIG. 27 is a rear-facing, exploded perspective view of the instrument panel of FIG. 25;

FIG. 28 is a front view of the instrument panel of FIG. 25;

FIG. 29 is a top view of the card module of FIG. 25;

FIG. 30 is a bottom view of the card module of FIG. 25;

FIG. 31 is a left view of the card module of FIG. 25; and,

FIG. 32 is a right view of the card module of FIG. 25.

The broken lines showing an electronic device are included for the purpose of illustrating environmental structure and form no part of the claimed design.
